UNITED STATES PATENT OFFICE.

WILLIAM APPLETON, OF ATTLEBORO, MASSACHUSETTS, ASSIGNOR TO
THE HORTON ANGELL COMPANY, OF ATTLEBORO, MASSACHUSETTS,
A CORPORATION OF MASSACHUSETTS.

STUD OR BUTTON.

SPECIFICATION forming part of Letters Patent No. 761,935, dated June 7, 1904.

Application filed May 10, 1900. Serial No. 16,120. (No model.)

To all whom it may concern:

Be it known that I, WILLIAM APPLETON, of Attleboro, county of Bristol, in the State of Massachusetts, have invented certain new and useful Improvements in Studs or Buttons, of which the following is a specification, reference being had to the drawings forming a part thereof.

The invention relates to studs or buttons, and is intended more especially for use in connection with buttons such as shirt-studs, which should be of such construction that they may be conveniently inserted through the materials without wrinkling or bending the same and which should be securely held in place in the materials after being inserted.

The purpose of the invention is to provide a button or stud which is simple in construction, may be manufactured cheaply, and which may be conveniently applied to or removed from the materials or garment with which it is used.

The button embodying the invention is provided with a cross-bar which when the button is in place lies along the under side of the materials at right angles to the post or shank of the button and extends from each side of said post. The head has a sliding connection with the cross-bar, so that the post or shank of the button may be moved to the end of the bar when the button is to be inserted in or removed from the materials. With the shank of the button at the end of the cross-bar the materials may readily pass along the bar and onto the shank. The bar being thus brought onto the side of the materials opposite to the head may then be moved longitudinally to bring the head into a position between the ends of the bar. The bar then prevents the materials from passing off the shank of the button. The frictional engagement of the connections between the head and bar may be relied upon to hold the bar and head in their relative adjusted positions—that is, with the head at the end of the bar or at a position intermediate the ends of the bar; but it is preferred to employ a catch, as with such a con-

struction the parts are more positively retained in their relative positions.

In explaining the invention more in detail reference will be made to the drawings, in which—

Figure 1 is a sectional view of a button embodying the preferred form of the invention; Fig. 2, a bottom view of the cross-bar; Fig. 3, a detail of the slide, and Fig. 4 a cross-sectional view.

In the construction of the button or stud shown in the drawings the sliding connection between the head A and the cross-bar B is made by making the bar hollow and mounting a slide therein, which is connected with the head A. The bar is in the form of a hollow tube closed at the ends and provided with a longitudinal slot b, extending from one end to near the middle of said bar. The slide for connecting the head and bar is in the form of a rod c, which fits within the tube B and is bent at right angles near its end to form a post c', which projects beyond the slot b and to which the head A is secured. The rod c extends longitudinally within the cross-bar and is of such length that the head and cross-bar will be firmly united, and the strains tending to draw the slide through the slot will be efficiently resisted without injury to the hollow tube. It is preferred to make the rod c of such length that it will extend substantially to the end of the slot b when the shank of the stud is flush with the end of the cross-bar, as with such construction a tube of smaller diameter and one made of thinner stock may be successfully employed. The head is provided with a tubular projection a, which fits over the post c' and is preferably of the same diameter as the tube B, said post and tube forming the shank of the button. The end b' of the bar forms a stop for limiting the movement of the slide c in one direction, and the end b'' of the slot b forms a stop for limiting the movement in the other direction. When the button is to be inserted through the stud-holes of a shirt-bosom, for instance, the head A is moved toward the end b' of the cross-bar until the

slide strikes the end of the bar, at which time the shank of the button will be flush with the end of the bar and at right angles thereto. The cross-bar and head may be retained in this position by the friction between the slide and cross-bar or by a catch, and the bar B may be thrust through the stud-holes, the end of the bar preferably being rounded or pointed to facilitate its entry. The entire bar is 10 thrust through the materials and also the shank a', the bar then lying along the inner surface of the materials. The end of the bar is preferably rounded or beveled on the side opposite the slot b, as shown, to facilitate the 15 passage of the stud through the materials. The bar B is now moved longitudinally along the slide c until the post c' strikes the end of the slot b. With this construction the head remains at the end of the bar B when moved 20 there until it is again moved to the middle of the bar, and the button can be more conveniently applied than can those buttons in which a spring-pressed plunger is employed, which must be held against the tension of the 25 spring by one hand while the button is being applied with the other hand.

The friction between the slide c and bar B may be sufficient to retain the slide and bar in their relative positions, and this friction 30 may be and preferably is increased by providing the slide c with spring-fingers c², formed by splitting the end of the rod c. These spring-fingers may be provided with bosses or projections c³, arranged to engage 35 holes b³ in the bar B and form catches for more positively retaining the head in its adjusted position. The bosses c³ may be formed on one or both of the fingers c² and may co-operate with holes on either side or both sides 40 of the bar B.

What I claim as my invention, and desire to secure by Letters Patent, is—

1. A stud or button comprising a hollow cross-bar having a longitudinal slot extending 45 a portion of the length of said cross-bar, a sliding member arranged to slide in the un-slotted portion of said cross-bar, said sliding member being provided at one end with a post rigid with said sliding member and extending through said longitudinal slot and provided with a head.

2. A stud or button comprising a hollow cross-bar having a longitudinal slot, a rigid L-shaped sliding member having one leg arranged 55 to slide in said cross-bar, the other leg of said L-shaped member projecting through said slot and provided with a head.

3. A stud or button comprising a hollow cross-bar having a longitudinal slot, a sliding

member arranged to slide in said cross-bar 60 and having a post rigid with said sliding member at one end projecting through said slot, a head secured to said post, and means for retaining said sliding member in its adjusted position. 65

4. A stud or button comprising a hollow cross-bar, having a longitudinal slot, a slide in said cross-bar having a post projecting through said slot, a head secured to said post, and one or more spring-fingers on said slide. 70

5. A stud or button comprising a hollow cross-bar, having a longitudinal slot, a slide extending longitudinally in said cross-bar and having a post at one end projecting through said slot, a head secured to said post, and a 75 spring-catch for retaining the slide in its adjusted position.

6. A stud or button comprising a hollow cross-bar, having a longitudinal slot, a bar sliding therein having spring-fingers at its 80 end, one or more bosses on said fingers, one or more recesses in said tube to co-operate with said boss or bosses, a post projecting from said slide through said slot and a head secured to said post. 85

7. A stud or button comprising a post with a head mounted thereon, said post having a laterally-bent portion, a cross-bar, a sliding connection between said post and cross-bar and one or more spring-fingers for retaining 90 the cross-bar in its adjusted position.

8. As an improved article of manufacture, a button or stud comprising a slotted barrel, a head provided with a post mounted to slide in said barrel, a foot projecting at right angles to the post and a spring-toe projecting 95 from said foot in frictional contact with the inner surface of the barrel.

9. As an improved article of manufacture, a button or stud comprising a slotted barrel, 100 a head provided with a post mounted to slide in said barrel, a cylindrical foot projecting at right angles to the post, and a thinner spring-toe projecting from said foot in frictional contact with the inner surface of the barrel. 105

10. A stud having a shank provided with a lateral resilient extension, and a shoe having a bore adapted to receive said extension, substantially as specified.

11. A stud having a shank provided with a 110 lateral curved resilient extension, and a shoe having a slotted bore adapted to receive such extension, substantially as specified.

WILLIAM APPLETON.
